UNITED STATES PATENT OFFICE

WILLIAM T. BRADBURY, OF KANKAKEE, ILLINOIS, ASSIGNOR TO FLORENCE STOVE COMPANY, OF BOSTON, MASSACHUSETTS, A CORPORATION OF MASSACHUSETTS

DESIGN FOR A GAS STOVE

Application filed December 14, 1931. Serial No. 42,074. Term of patent 7 years.

To all whom it may concern:

Be it known that I, WILLIAM T. BRADBURY, a citizen of the United States, residing at Kankakee, in the county of Kankakee and State of Illinois, have invented a new, original, and ornamental Design for Gas Stoves, of which the following is a specification, reference being had to the accompanying drawing, forming part hereof.

The figure is a perspective view of a gas stove, showing my new design.

The design is especially characterized by

the provision on the stove front of a plurality of similarly formed closure members, with a horizontal ledge extending along the ends and front of the stove body along the lower edge thereof, and a similar ledge extending parallel to and spaced a substantial distance above said lower ledge and along the front and ends of the stove, substantially as shown.

I claim:

The ornamental design for a gas stove, substantially as shown and described.

WILLIAM T. BRADBURY.
